UNITED STATES PATENT OFFICE.

ELMER N. DOWNES, OF CHARLOTTE, NORTH CAROLINA, ASSIGNOR TO J. & D. TIRE COMPANY, OF CHARLOTTE, NORTH CAROLINA, A CORPORATION OF DELAWARE.

DESIGN FOR A NON-SKID TIRE.

53,146.

Specification for Design.

Patented Apr. 1, 1919.

Application filed January 27, 1919. Serial No. 273,485. Term of patent 14 years.

To all whom it may concern:

Be it known that I, ELMER N. DOWNES, a citizen of the United States, residing at Charlotte, in the county of Mecklenburg and State of North Carolina, have invented a new, original, and ornamental Design for a Non-Skid Tire, as shown in the accompanying drawing, forming part of this specification.

In said drawing Figure 1 is an exterior face or edge view of part of the tire showing the peculiar bas relief ornamental configuration thereof. Figs. 2 and 3 are transverse sectional views respectively taken on lines 2—2 and 3—3, Fig. 1.

The design extends longitudinally and circumferentially of the tire tread. Its distinguishing features are opposed pairs of similar approximately U-shaped figures 1, 1 and 2, 2 which are arranged in alternation around the tread, adjacent pairs of figures facing in opposite directions; the parts between the opposed concave portions of adjacent pairs of such figures form approximately diamond shaped figures 3; and the parts between the opposed base portions of

adjacent pairs of figures 1 and 2 form approximately oval shaped figures 4. At the outer sides of and adjacent the figures 4 are parts 4^a which also form approximately diamond shaped figures.

The adjacent transversely alined figures 4^a, 4, 4^a are connected by intermediate stems 4^b; the adjacent longitudinally alined figures 4^a are connected by longitudinal stems 4^c; the adjacent longitudinally alined figures 4 are connected by longitudinal stems 4^d; and the transversely alined figures 3 are connected with the stems 4^c and 4^d by short stems 3^a and 3^b as shown.

The U-shaped figures 1 and 2 are shown depressed, and the other parts of the design raised, which enhances the appearance of the design.

I claim:

The ornamental design for a non-skid tire substantially as shown and described.

ELMER N. DOWNES.

Witnesses:

JOSEPH Q. TAYLOR,
HARRY O. FOSTER.
